REFRIGERATOR CAR

Allan N. Campbell, Montreal, Quebec, Canada

Application January 21, 1952, Serial No. 267,336

15 Claims. (Cl. 62—117)

1

This invention relates to improvements in refrigerator cars and the primary object of the invention is to provide a mechanically refrigerated refrigerator car in which the entire refrigerating mechanism is located externally of the normal load space of the car whereby the car interior is available throughout its entire length and width and to at least its normal loading height for load stowage. A further object is to provide a refrigerator car as aforesaid in which the powering means and all the refrigerating mechanism except the evaporator is suspended beneath the car in suchwise as to be readily accessible for inspection and servicing. A still further object is to provide a refrigerator car as aforesaid in which the refrigerating mechanism is primarily diesel engine powered. Another object is to provide a refrigerator car having diesel engine powered mechanical refrigerating mechanism in which a diesel engine-generator-alternator set is so mounted beneath the car that it may be easily and quickly moved, by one man, from its operating position beneath a car to an inspection and servicing position at one side of the car and as easily and quickly returned to operating position. Still another object is to provide such disposition on a car of mechanical refrigerating mechanism and powering means therefor as will be applicable to refrigerator cars of standard design and construction, with little or no structural change in the cars, whereby the invention may be applied to existing cars quite as well as to new cars. Various other objects and the advantages of the invention may be ascertained from the following description and the accompanying drawings.

It has been demonstrated that the operating cost of mechanically refrigerated cars may be sufficiently less than the operating cost of water-ice and salt refrigerated cars to more than compensate for the higher capital cost of refrigerating mechanism as compared with the capital cost of water-ice and salt refrigerating equipment but the great disadvantage of mechanical refrigeration has been the substantial amount of space within the car occupied by the refrigerating mechanism and its power plant, with consequent reduction in load stowage space and loss of car earning power. To minimize this disadvantage, the compartment containing the primary powering means has been made as small as possible but this precludes inspection and servicing of the powering means in situ and necessitates removal of the powering means from the car, as by mounting it on a slide for movement through a doorway in the car side.

2

It has been proposed to avoid loss of stowage space in the car by mounting the powering means and elements of the refrigerating mechanism under the car body but heretofore this has not been found practicable because of space limitations and because of inaccessibility of the powering means for inspection and servicing and because of the lack of any practicable means for moving the powering means to a position where it may be inspected and serviced. The only practical type of primary powering means is an internal combustion engine-generator-alternator set and for dependability and economy of operation a diesel engine is preferable but has not heretofore been found practicable because of the size and weight of a diesel-electric set suitable for primary powering of a refrigerator car refrigerating mechanism. The vertical space between the under floor of a refrigerator car and the plane of over-rail clearance, below which nothing may project, is not sufficient to accommodate a suitable diesel-electric set. If projection of the engine set below the over-rail clearance is sought to be avoided by allowing the engine to project through and above the car underfloor, inspection and servicing in situ are impossible and, because of the projection of the engine through the car floor, it is likewise impossible, because of the car side sill, to move the engine set transversely beyond the car in the same manner as when it is located within the car. Moreover, feasibility of lowering the engine set for inspection and servicing sufficiently to clear the car underfloor is strictly limited by proximity of the railway track rails and by the weight of the engine set. The maximum clearance that can be provided between the base of a suitable diesel-electric set and the top of rail is only about 8 inches and the weight of the set is in the neighborhood of 2000 pounds. Furthermore, it is necessary in order to avoid prohibitive car operating costs through lost running time and, more important, for preservation of a perishable load in the car that the engine set be so mounted as to be easily and quickly accessible for inspection and servicing at any point along the route of the car and without employment of external facilities. In practice, it should be possible for one man to inspect and give normal servicing to an engine set and return it to operation in a matter of 10 to 15 minutes. It will be realized from the foregoing that the limitations of space and time and the weight of the engine set pose a very considerable problem which must be solved before it becomes practicable to mount the primary powering means of a mechanical refrigerating set beneath a car body.

The present invention provides a complete solution of the foregoing problem and consists, essentially, in mounting all parts of a mechanical refrigerating equipment (expect the evaporator) and the primary powering means therefor at suitable points beneath a car body, the primary powering means being mounted on a cradle swingingly suspended from the car underframe for movement transversely of the car from an operating position close under the car to an inspection and servicing position at one side of the car, and vice versa, the suspension means including means to counterbalance the weight of the primary powering means and suspension means during the aforesaid movements.

In greater detail, the invention consists in the features and combinations of features herein disclosed, together with all such modifications thereof and substitutions of equivalents therefor as are within the scope of the appended claims.

In the accompanying drawings which illustrate that embodiment of the invention now preferred, but to the details of which the invention is not confined:

Fig. 1 is a plan view of a refrigerator car underframe showing the disposition of power plant and refrigerating plant units thereon.

Fig. 2 is a cross-sectional view of the car frame at the line 2—2 of Fig. 1, indicating the suspension of a power plant unit and a compressor-condenser unit.

Fig. 3 is a cross-sectional view of the car frame at the line 3—3 of Fig. 1, showing the suspension and form of the fuel tank.

Fig. 4 is a cross-sectional view of a car at the line 4—4 of Fig. 1, showing the suspension of the battery and the power plant and refrigerating mechanism controls and the location of the refrigerant evaporator and air circulating means.

Fig. 5 is a plan view of the mid portion of the roof frame of the car of Fig. 1, showing the suspension therefrom of the refrigerant evaporator and the air circulating means.

Fig. 6 is a partial cross-sectional view of a car underframe at the line 6—6 of Fig. 1, on an enlarged scale, illustrating the suspension mounting of the power plant.

Fig. 7 is a side elevation of a portion of car underframe, on the same scale as Fig. 6, showing the suspension of the power plant.

Fig. 8 is a plan view of a portion of car underframe, on the same scale as Fig. 6, further showing the power plant suspension means.

Referring more particularly to the drawings and initially to Figs. 1 to 5 thereof, 11 designates the center sill, 12 the side sills, 13 the body bolsters, 14 the transoms and 15 the intermediate cross members of a car frame. Toward one end of the frame, between a transom 14 and the remote cross member 15 at the same end of the car, and between the center sill and one of the side sills, there are suspended an encased power plant designated as a whole by the numeral 16 and, between the center sill and the other side sill, an encased, electric motor driven refrigerant compressor, heat exchanger, condenser and receiver unit designated as a whole by the numeral 17. The power plant is an internal combustion engine-generator-alternator set, the engine being preferably a diesel engine. In the mid portion of the car, between the transoms 14, there is suspended on one side of the center sill a storage battery 18 and on the other side of the center sill a power plant and refrigerating plant

control means designated as a whole by the numeral 19. Toward the opposite end of the car from the power plant and between the cross members 15 there is suspended a fuel tank 20 which preferably extends from side to side of the underframe and has a central portion 21 of reduced depth to underlie the center sill. The side portions of the tank extend upwardly from the level of the bottom of the center sill and are provided under or adjacent the side sills with filling necks 22 and at convenient points with overflow and venting means 23. The bottom 24 of the tank slopes downwardly from the sides toward the center line of the underframe and, near its lowest point, connects with a fuel feed pipe 25 which extends to the power plant and is provided near the same with a quick operating coupling of any suitable sort, indicated at 26, which may include automatic cutoff means to prevent escape of fuel when the coupling is uncoupled. It is to be noted that all the aforesaid suspended elements, while they approach close to it, do not depend below the standard over-rail clearance indicated by the lines 27.

In the mid portion of the car, immediately under the roof frame 28, a sub-frame 29 is suspended from the roof frame and carries a refrigerant evaporator of any suitable sort, indicated at 30, and preferably formed of two independent sections, each having its own expansion valve 31. Preferably the sub-frame 29 also carries blowers 32 to force air over the evaporators and circulate it through the car, the blowers being driven by electric motors 33 enclosed in a housing 34 adapted to exclude motor heat and odours from the interior of the car.

Alternatively, the blowers and motors may be omitted and the evaporators may be mounted in tanks close under the roof (not shown) in which they may be submerged in brine.

Referring now to Figs. 6, 7 and 8 which illustrate the power plant and the details of its suspension means, 35 designates a cradle on which mechanical elements of the power plant, designated as a whole by the numeral 36, are mounted by means of lugs or flanges 37 resting on the cradle. The cradle comprises spaced outer and inner longitudinal members 38 and 39, respectively, connected at adjacent ends by transverse end members 40 and 41 riveted thereto to constitute a rectangular frame. These members are preferably angle bars arranged to present upstanding flanges 42 at the periphery of the frame and other flanges 43 extending inwardly of the frame from the lower edges of the flanges 42, as best shown in Fig. 8. The supporting lugs or flanges 37 of the power plant rest on the inwardly extending flanges 43 of the members 38 and 39 and may be connected thereto by bolts passing through apertures 44 in the flanges 43. The power plant is preferably a diesel engine-generator-alternator set of standard construction.

The cradle 35 is suspended at each end from the car underframe by parallel links 49 and 50, pivotally connected at their lower ends to brackets 51 fixed to the cradle end members 40 and 41. The upper ends of these links are pivotally connected to brackets 52 and 53 fixed, respectively, to the transom 14 and to the cross frame member 15, adjacent the ends of the cradle, as shown in Fig. 1. The link 50 at each end of the cradle has an arm 54 rigidly connected to it and extending, preferably from its upper end, to

ward the center sill 11, the link and arm constituting a bell-crank lever fulcrumed at the upper pivotal point of the lever 50. At each end of the cradle, a lever 55 is pivotally mounted near one of its ends in the adjacent bracket 52 or 53 and provides a short arm above the pivotal point and a long arm below. The upper end of each lever 55 is pivotally connected to one end of a link 55^a, the other end of which is pivotally connected to the free end of the bell-crank arm 54. The lower end of each lever 55 is pivotally connected to one end of a counterbalance device 56, the other end of which is anchored to a bracket 57 fixed to the center sill. Each counterbalance device is preferably of the elongatable link-compression spring type, comprising a pair of oppositely facing U-shaped tension members 58 arranged in parallelism and interdigitating relation and connected at their closed ends to the lever 55 and to the bracket 57, respectively; a spring seating cup 59 at the open end of each said tension member, retained by adjusting nuts 60 threaded on the end portions of the member arms and apertured for sliding engagement of the arms of the other member 58 therein; and a helical spring 61 surrounding the members between the cups 59 and in compression between the cups.

The cradle and its suspension means are shown in full lines in Fig. 6 in their normal travelling position in which they support the power plant 36 in normal operating position beneath the car underframe. It will be noted that in this position the links 49 and 50 incline from their upper pivotal points toward the central vertical plane of the car. The links have capacity for outswinging movement to an opposite inclination to carry the cradle through a descending and then ascending arcuate path, laterally of the car to a position in which the power plant is located beyond the side of the car, all as shown in single dot and dash lines. During this movement the bell-crank arms 54 swing downwardly. The upper pivotal points of the links 50 and the pivotal points of the levers 55 are so related that during an initial part of the outswinging movement of the links and the downward movement of the bell-crank arms 54, the links 55^a move the levers 55 and cause their lower arms to swing outwards, as shown in double dot and dash lines, to elongate the counterbalance devices, drawing the inner spring seats 59 outwards and compressing the springs 61 to oppose the downward movement of the cradle and power plant. At an intermediate point in the travel of the links and cradle, when the uppermost pivotal points of the levers 55, the upper pivotal points of the levers 50, and the pivotal connections of the bell-crank arms 54 and links 55^a are in alignment, the outswinging movement of the levers 55 ceases. This intermediate point in travel is reached approximately when the cradle is at the lowest point in its arcuate path of travel. During further outswinging movement of the links 49 and 50 and the cradle, the aforesaid relation of pivotal points permits the lower arms of the levers 55 to swing inwardly. During this inswing of the levers 55, the reflex action of the compressed springs 61 is transmitted through the levers 55, links 55^a and the bell-crank arms 54 to the links 50 to urge them to further outswinging movement, with consequent upward movement of the cradle and power plant in their arcuate path of travel. The springs 61 have combined effect to approximately counterbalance the action

of gravity on the cradle and power plant when at the extremes of their movement, so that the cradle and power plant tend to remain at either extreme of their movement. While the links 49 and 50 have been shown as of equal length and parallel so that the inclination of the cradle (shown as 0°) is not altered during cradle travel, this is not necessarily the case.

In order to hold the cradle and power plant thereon in their normal travelling and operative position, a locking hook 62 is pivotally mounted on a bracket 63 fixed to and extending inwardly from the cradle member 39 (Figs. 6 and 8) and is adapted to have hooking engagement with a locking rail 64 carried by brackets 65 depending from the center sill 11. This hook is connected by a rod 66 with an operating lever 67 pivotally mounted on a bracket 68 fixed to the upright flange of the outer cradle member 38. When the lever 67 is moved to parallelism with the member 38, it positively moves the hook 62 into locking engagement with the rail 64 and when the lever is swung outwardly from the cradle, it moves the hook to disengage the rail 64. The lever 67 is provided with a captive locking pin 69 to pass through the lever and through a lug 70 springing from the bracket 68, when the lever is in position to hold the hook 62 in cradle locking position.

Means is provided to hold the cradle against being moved longitudinally of the car by reason of inertia of the cradle when the speed of car movement alters. This means comprises tapered plug members 71 fixed to one of the rail 64 or the cradle member 39, near the ends of the cradle, and socket members 72 fixed to the other of said rail and cradle in positions to receive the plug members. The socket members present converging surfaces spaced in the direction of car length to receive between them the converging surfaces of the plug members, thereby to position the cradle in the longitudinal direction of the car. When the locking hook 62 is moved into engagement with the locking rail 64 it causes the plugs 71 to wedge into the sockets 72 to hold the cradle against movement toward the center sill, as well as against movement longitudinally of the car. As the hook 62 holds the cradle against movement away from the center sill, it will be seen that the cradle and power plant are held against any movement relative to the car underframe.

To initially lock the cradle in its outswung and in its inswing positions, double ended latches 73 are pivotally mounted on the brackets 52 and 53 in position to be engaged by lugs 74 on the links 49, when the links reach either extreme of their movement. These latches operate automatically to hold the cradle against rebounding when it is moved to its inner position and the members 71 and 72 engage and also to lock and hold the cradle in its outswung position while the power plant is being serviced. As the springs counterbalance the weight of the power plant at the extremes of its travel, it will be understood that but little holding effect is required of the latches. The latches 74 may be of any suitable sort, those illustrated being of the gravity type and including weighted actuating levers 75 having 180° of movement relatively to the latches 73 so as to power them for latching action selectively in either direction.

As previously stated, and as best shown in Fig. 6, the dimensions of a diesel engine suitable for primary powering of a refrigerator car refrigerating mechanism are such that there is not suffi-

cient vertical space between the over-rail clearance line, indicated at 27, and the under floor 76 of the car to accommodate the engine. Even when the cradle 35 is located practically at the clearance line and the engine is set as low as is possible in the cradle, part of the engine will extend through and above the floor 76 and almost up to the inner floor, or drip pan, 77 which underlies the usual floor racks. A housing 78 is mounted on the underfloor to cover the upwardly projecting part of the engine and exclude therefrom insulating material which usually fills the space between the floors and leave a clear path for the lateral movement of the engine from its operating position and return thereto. It will also be seen that the lengths and arcuate movement of the links 48 and 50 are such that the cradle just clears the top of rail when it is at the lowest point in its travel, and that the highest point of the engine will just pass under the side sill 12.

The power plant is enclosed in a generally rectangular housing comprising essentially an upper stationary section 79 depending from the underfloor 76, a lower movable section 80 mounted on the cradle, and a removable outer section 81. The inner and end walls of the upper and the lower sections are arranged to register with one another and to meet in edge to edge abutting relation and the removable section extends between the outer walls of the upper and lower sections. The outer wall 82 of the upper section is located outwardly of the vertical plane of the outer cradle member 33 and depends only a short distance from the floor 76, so as to permit passage under it of the engine but the inner wall 83 may, and preferably does, depend considerably more. The movable part 80 of the housing includes a low outer wall 84 which extends from the cradle at an angle determined by the clearance line indicated at 27 to the vertical plane of the upper section outer wall 82. This wall 84 is formed with an inwardly offset portion 85 exposing the cradle member 33 and providing a recess for accommodation of the locking lever 67. The inner wall 86 of the movable section need extend upwardly from the cradle only enough to carry the engine muffler 87. The end walls of the upper and the lower housing sections may be of any vertical dimensions desired and their meeting edges 88 may follow any desired line, such as the uniform inclination downwardly from the outer wall, as indicated. The outer removable section 81 extends from end to end of the housing and from the upper section outer wall 82 to the lower section wall 84 and may be suspended from the upper section wall 82 by hinges 89 preferably of a hook-on type permitting easy removal of the section. Any suitable fastening means, such as the bolts 90, may be provided near the lower edge of the section to secure it in closed position. A handle 91 may be provided on the removable section for convenience in lifting and removing it. A second handle 92 is provided on the outer wall of the lower housing section to serve for drawing the cradle and power plant out from under the car. The meeting edges of the housing sections are formed in any way suitable for exclusion of dust from the interior of the housing.

Although not shown, it will be understood the usual controls are provided, also the usual and necessary fluid and electrical connections between elements of the apparatus and between them and the controls.

When it is required to service the power plant,

the removable housing section is removed, the fuel line disconnected at 26, the lever 57 unlocked and swung out from the cradle to disengage the hook 62 from the locking rail 64 and the latches 5 74 released. The cradle with the power plant thereon may then be very easily pulled out from beneath the car, by one man. The upper part 79 of the power plant housing remains under the car and the lower part, which does not interfere with servicing, moves with the cradle. When servicing is complete, the cradle with the power plant is pushed back under the car, where it is automatically held by the latches 73 until the lock 62 is actuated by the lever 67. In the first 10 half of both the outswinging and the inswinging movements, when the cradle is descending to the lowest part of its arcuate path of travel, the action of gravity on the moving mass is preferably slightly more than counterbalanced by compression of the springs 64, so that the structure does not move of itself but requires a slight outward pull or inward push. In the second half 15 of both swinging movements, when the mass is rising from the lowest part of its path, the reflex action of the springs again substantially counterbalances the action of gravity and tends to move the structure to the end of its path, with automatic latching effect. It may happen on occasion that the only inspection or servicing required can 20 be effected on removal of the housing section 81, without swinging the power plant out from under the car. It will be obvious that inspection and servicing of a power plant mounted according to this invention may be accomplished more easily 25 than if the power plant was mounted within the car, as the operation is performed conveniently close to ground level, instead of from a platform or ladder, and the operator can move freely around the plant. If the power plant suffers from 30 disorder that cannot be cured by ordinary servicing, the entire plant may be removed very quickly and easily from the cradle by removing a few anchor bolts and then replaced by another plant. Such an operation is more easily performed from 35 ground level than if the plant is at car floor level.

Having thus described my invention, I claim:

1. A refrigerator car comprising an underframe and a roof frame and mechanical refrigerating means for said car, including an internal combustion engine-generator set as powering means and a refrigerant evaporator; all said refrigerating means excepting the refrigerant evaporator being suspended from and beneath the underframe on opposite sides of the longitudinal and transverse center lines thereof, while said evaporator is suspended from and close beneath the roof frame, approximately midway between the ends of the car; and means permanently connected 50 to said powering means solely suspending the latter and swingingly supporting it for movement laterally of the car from an operating position beneath the car to a servicing position at one side of the car.

2. A refrigerator car comprising an underframe and elements of a mechanical refrigerating means for the car including an internal combustion engine-generator set as powering means; a cradle to support said powering means; means to suspend the cradle from the underframe with capacity to support the cradle for movement from a position beneath the underframe to a position at one side of said frame; and means to control the speed of movement of the cradle and powering 60 means thereon.

3. Structure according to claim 2 including means to lock the cradle at each extreme of its movement to the underframe and means to lock the cradle when beneath the underframe against movement longitudinally of the car and relatively thereto.

4. A refrigerator car comprising an underframe and elements of a mechanical refrigerating means for the car including an internal combustion engine-generator set as powering means; a cradle to support said powering means, said cradle being movable from a position beneath the underframe to a position to one side of said frame; suspension links pivotally connected between the ends of said cradle and the underframe and inclining upwardly toward a side of the underframe when the cradle is beneath the frame and being oppositely inclined when the cradle is positioned to one side of the frame, whereby the cradle is constrained to move downwardly and then upwardly in an arcuate path; and means to substantially counterbalance the weight of the cradle and power plant thereon when beneath the underframe and when at one side thereof.

5. A refrigerator car according to claim 4 in which the counterbalance means includes springs and means connected between the cradle and the underframe to increasingly load said springs during downward movement of the cradle in its arcuate path and to transmit reflex action of said springs to urge the cradle to upward movement in its arcuate path.

6. A refrigerator car according to claim 4 including means to lock said cradle against swinging movement when at each of its terminal positions; and means to hold the cradle against movement in the longitudinal direction of the underframe, relatively thereto, when positioned beneath the underframe.

7. A refrigerator car comprising an underframe and elements of a mechanical refrigerating means for the car including an internal combustion engine-generator set as powering means; a cradle to support said powering means, said cradle being movable from a position beneath the underframe to a position to one side of said frame; suspension links pivotally connected between each end of said cradle and the underframe and inclining upwardly and away from the longitudinal center line of the car when the cradle is beneath the car and being oppositely inclined when the cradle is positioned to one side of the underframe, whereby the cradle is constrained to move in an arcuate path, first downwardly and then upwardly; an arm projecting rigidly from one of said suspension links at each end of the cradle; a lever pivoted intermediate its ends adjacent each said armed link; link connection between each of said arms and an end of the adjacent lever; a variable length link connected between the other end of each said lever and the underframe, including spring means; the angular relation of the suspension links and their arms and the relative locations of the pivotal points of the suspension links and the levers being such that, during downward movement of the cradle in its arcuate path, the springs are loaded and oppose cradle movement, and during upward movement of the cradle in its path, reflex action of the springs urges the cradle to such upward movement.

8. A refrigerator car comprising an underframe and elements of a mechanical refrigerating means for the car including an internal combustion engine-generator set as powering means; a cradle to support said powering means; a pair of links

at each end of the cradle pivotally connected at their lower ends to the cradle and pivotally connected at their upper ends to the underframe, with capacity to swingingly support the cradle for movement from a position beneath the underframe to a position at one side of the same; a lug on one of the links at each end of the cradle; latching means carried by the underframe at each end of the cradle, positioned to be engaged by said lugs at each extreme of link movement to releasably hold the cradle at the extremes of its movement.

9. A refrigerator car comprising an underframe and elements of a mechanical refrigerating means for the car including an internal combustion engine-generator set as powering means; a cradle to support said powering means; a pair of links at each end of the cradle pivotally connected at their lower ends to the cradle and pivotally connected at their upper ends to the underframe, with capacity to swingingly support the cradle for movement from a position beneath the underframe to a position at one side of same; a rigidly mounted locking rail carried by the underframe; means for positioning the cradle in the longitudinal direction of the underframe, when the cradle is located under the frame, and for holding it against movement longitudinally of the frame, comprising interengageable members on said cradle and frame; and means to positively lock the cradle against movement transversely of the underframe, thereby to ensure maintenance of effective interengagement of said interengageable members.

35. 10. Structure according to claim 9 in which the interengaging members comprise a plug member having substantially vertical surfaces converging in the transverse direction of the underframe, carried by one of said cradle and locking rail; and a socket member having substantially vertical surfaces converging similarly to the surfaces of the plug member, carried by the other of said cradle and locking rail in position for engagement with the plug member when the cradle is in its extreme inswing position beneath the underframe, with effect to position the cradle in the longitudinal direction of the underframe; and in which the locking means includes a hook pivotally mounted on the cradle; means to move said hook into hooking engagement with the rail, thereby to hold said cradle in its extreme inswing position and hold said plug and socket members in operative engagement for holding the cradle against movement longitudinally of the underframe.

1. A refrigerator car comprising an underframe including center and side sills and transverse members; a car underfloor resting on said underframe; a car upper floor spaced above the underfloor; an internal combustion engine-generator set normally disposed beneath the underframe and extending substantially from the over-rail clearance, below which no part of the car may depend, upwardly and through the underfloor; means swingingly suspending said engine-generator set from the transverse members of the frame for movement from a position beneath the underframe to a position at one side thereof, said means being adapted to cause the set to move in an arcuate path, the depth of which is such that the uppermost part of the set will pass under a side sill while the lowest part of the set will clear a railway track rail on which the car stands.

12. A refrigerator car comprising an under-

11

frame including a center and a side sill and transverse members connected between said center and side sills; a cradle frame to be disposed longitudinally of the underframe and therebeneath; a suspension link at each end of the cradle pivotally connected at its upper end to the underframe adjacent a side sill thereof and pivotally connected at its lower end to an end of the cradle, adjacent the outer longitudinal edge thereof; a bell-crank lever at each end of the cradle, pivotally connected at its elbow to the underframe, intermediate the side and center sills, and including a depending cradle suspending arm pivoted at its lower end to an end of the cradle adjacent the inner longitudinal edge thereof; said links and suspension arms being adapted to swing in vertical planes transverse of the underframe and to carry the cradle from an inner position beneath the underframe to an outer position at one side of the underframe; the second arm of each said bell-crank lever projecting toward the center sill; a lever at each end of the cradle, fulcrumed near one end to the underframe, intermediate said link and bell-crank lever; a connecting link extending from the upper end of each said lever to the free end of each said second bell-crank arm and pivotally connected to each; an elongatable link connected between the lower end of each said lever and the underframe adjacent the center sill thereof, including a spring in compression.

13. A refrigerator car comprising an underframe including a center sill and a side sill, and elements of a mechanical refrigerating means for the car including an internal combustion engine-generator set as powering means, said powering means being normally disposed beneath the underframe between the center and a side sill thereof; means to movably support the powering means in said normal position with capacity for movement transversely of the car from its said normal position to a position to one side of the car and for return to normal position, said supporting means being formed and adapted to lower the powering means as it moves transversely 45

12

of the car sufficiently to enable it to pass beneath the side sill; and means to oppose the downward movement of the powering means and to assist upward movement thereof during return to normal position.

14. A refrigerator car comprising, in combination, an underframe and mechanical refrigerating means for said car including an internal combustion engine-generator set, as powering means, located beneath the car; and means suspending said powering means from the underframe causing movement laterally of the car from an operating position beneath the car to a servicing position at one side of the car and for simultaneous movement downwardly and upwardly with respect to the car.

15. A refrigerator car comprising, in combination, an underframe and mechanical refrigerating means for said car including an internal combustion engine-generator set, as powering means, located beneath the car and projecting above the level of the lower edge of the underframe side sill when said powering means is in its lowest permissible travelling position; and means for suspending said powering means from the underframe and for moving the powering means laterally of the car between an operating and travelling position beneath the car and a servicing position at one side of the car and between servicing and operating positions and for lowering the powering means during movement from operating position sufficiently to permit its passage beneath the underframe side sill and for raising it during movement to operating and travelling position.
